RAILWAY-TRAFFIC-CONTROLLING APPARATUS

Application filed June 21, 1926, Serial No. 117,335. Renewed September 5, 1929.

My invention relates to railway traffic controlling apparatus, and particularly to apparatus of the type comprising means for supplying train controlling currents to the trackway and governing means on the train controlled by such currents. More particularly my present invention relates to the trackway portion of such apparatus.

In systems of the type described it is customary to supply the train controlling current to each track section from a source located adjacent the exit end of the section, and when two parallel sections of track are connected by a cross-over, the cross-over must also be supplied with train controlling current in order that the control of the train carried governing means may be continuous. My present invention relates to apparatus for supplying train controlling current to a cross-over under the conditions described above.

I will describe several forms of trackway apparatus embodying my invention, and will then point out the novel features thereof in claims.

In the accompanying drawings, Fig. 1 is a diagrammatic view illustrating one form of trackway apparatus embodying my invention. Figs. 2 to 5, inclusive, are diagrammatic views illustrating modified forms of the apparatus shown in Fig. 1 and also embodying my invention.

Similar reference characters refer to similar parts in each of the several views.

Referring first to Fig. 1, the reference characters A and B designate two parallel railway tracks over which traffic normally moves in the direction indicated by the arrows. The rails 1 and 1^a of track A are divided by means of insulated joints 2, into a plurality of successive track sections, only one of which, C—D, is shown in the drawing. In similar manner the rails 1 and 1^a of track B are divided to form a plurality of track sections, only one of which, E—F, is shown in the drawing. The two parallel sections D—E and E—F are connected by means of a cross-over X comprising two switches H^a and H^b. These switches may be operated, by means forming no part of my present in-

vention, in such manner that when one switch is in its normal position as shown in the drawing, the other switch also occupies its normal position to permit traffic to move along sections C—D and E—F; but that when one switch is moved to its reverse position the other switch also moves into its reverse position to permit traffic to move from section E—F through the cross-over X into section C—D. A circuit controller K is operated by switch H^a so that when the switches of the cross-over are in their normal positions contact 15—17 of circuit controller is closed. When the switches of the cross-over are reversed contact 15—17 is open and contact 15—16 is closed.

Each track section of each of the stretches of track A and B is provided with a track relay designated by the reference character R with an exponent corresponding to the location and connected with the rails adjacent the entrance end of the associated section. Each track section is also supplied with track circuit current from a suitable source such as a battery constantly connected across the rails adjacent the exit end of the corresponding section and designated by the reference character L with a suitable distinguishing exponent.

Means are also provided for supplying alternating train controlling current to the rails of each section. For this purpose each section is provided with a track transformer designated by the reference character T with an exponent corresponding to the location and having a secondary 4 connected across the rails of the associated section in series with the track battery L and the usual resistance 6 and reactance 7. Alternating current is at times supplied to primary 5 of each track transformer T from secondary 11 of a line transformer G, primary 12 of which is constantly supplied with alternating current from a suitable source such as an alternator M over line wires 3 and 3^a. Assuming that the switches of cross-over H are in their normal positions to permit traffic to move along section C—D and along section E—F, and that relay R^f is energized, current flows from secondary 11 of transformer G, through wires 100

18 and 19, front contact 13 of relay R^F , wire 20, contact 15—17 of circuit controller K, wire 21, primary 5 of the transformer T^F , and wires 22, 23 and 24 back to secondary 11 of transformer G. Train controlling current is then supplied to the rails of section E—F. If relay R^D is energized, train controlling current is supplied to the rails of section C—D from transformer T^D , the primary circuit for this transformer passing from secondary 11 of transformer G, through wires 18 and 25, front contact 14 of relay R^D , wires 26 and 27, primary 5 of transformer T^D , and wires 28 and 24 back to secondary 11 of transformer G. It will therefore be seen that when the switches of cross-over X occupy their normal positions, each section C—D and E—F is supplied with train controlling current if the relay for the section next in advance and for the same track is energized.

The rails of the cross-over X are divided, by means of insulated joints 2, to form a sub-section P—S. An auxiliary transformer T^X has its secondary 8 connected across the rails adjacent the exit end of subsection P—S in series with an impedance 10, and this transformer supplies train controlling current to the rails 1 and 1^a of the cross-over X. The primary 9 of transformer T^X is provided with a circuit which may be traced from secondary 11 of transformer G, through wires 18 and 25, front contact 14 of relay R^D , wires 26, 29 and 30, primary 9 of transformer T^X , wires 32, 23 and 24, back to secondary 11 of transformer G. It follows that the rails of the cross-over are supplied with alternating train controlling current by transformer T^X when relay R^D is energized but not when this relay is de-energized. When the switches H of the cross-over X are reversed to permit traffic to move from track B into track A circuit controller K is reversed and the circuit previously traced for transformer T^F is interrupted. But a new circuit is now closed for this transformer from secondary 11 of transformer G through wires 18 and 25, front contact 14 of relay R^P , wires 26, 29 and 31, contact 15—16 of circuit controller K, wire 21, primary 5 of transformer T^F , and wires 22, 23 and 24 back to secondary 11 of transformer G. When this circuit is closed, current is supplied to primary 5 of transformer T^F even though relay R^F be de-energized.

It will be seen from the foregoing that if the switches of the cross-over are reversed and a train moves into section E—F this train will be supplied with train controlling current between point E and switch H^B from transformer T^F provided relay R^D is energized. As the train moves into sub-section P—S of the cross-over, it receives train controlling current from transformer T^X , and when the train leaves the cross-over and proceeds along section C—D, it receives train

controlling current from transformer T^D . It follows that, so far as traffic conditions in advance of points D and F are concerned, the supply of train controlling current to the train when the switches of the cross-over are reversed is controlled solely by relay R^D and that the train is supplied continuously with train controlling current as it moves from one section to the other over the cross-over if this relay is energized.

Referring now to Fig. 2, the apparatus is similar to that shown in Fig. 1 except that the primary 9 of transformer T^X is connected with the rails of section C—D adjacent the switch H^A instead of receiving energy direct from transformer G over a contact of relay R^P . Transformers T^F and T^D are controlled in the same manner as in Fig. 1. When the transformer T^D is supplying train controlling current to section C—D, current flowing in primary 9 of the transformer T^X causes a similar current to be supplied to the rails of section P—S by secondary 8 of this transformer. The operation of the apparatus is similar to that described in connection with Fig. 1 and will be understood from the drawing without further explanation.

Referring now to Fig. 3, the cross-over X is divided into two sub-sections P—Q and Q—S. The upper rail 1 of sub-section Q—S is constantly connected with rail 1^a of section C—D at the frog 38 of the switch H^A . The rail 1^a of sub-section Q—S is connected, adjacent the exit end of the sub-section, with rail 1 of section C—D by means of a conductor 35. It will therefore be plain that when section C—D is being supplied with train controlling current from transformer T^D , this current will flow through the rails of sub-section Q—S so that a train occupying this sub-section will be supplied with train controlling current.

The circuit controller K, in addition to contact 15, carries two other contacts 33 and 34, arranged to be closed only when the switches of the cross-over are reversed. When contact 33 is closed the left-hand end of rail 1^a of sub-section Q—S is connected with the right-hand end of rail 1^a of sub-section P—Q, and when contact 34 of circuit controller K is closed the left-hand end of rail 1 of sub-section Q—S is connected with the right-hand end of rail 1 of sub-section P—Q. In explaining the operation of the apparatus I will assume that relay R^D is energized and that the switches of the cross-over are reversed. Contact 15—17 of circuit controller K is therefore open so that the circuit for transformer T^F is interrupted. A train in section E—F between E and H^B is supplied with train controlling current under these conditions from transformer T^D , this current flowing from the right-hand terminal of secondary 4 of transformer T^D , through reactance 7, rail 1 of section C—D, conductor 35, rail 1^a

of sub-section Q—S, contact 33 of circuit controller K, rail 1^a of sub-section P—Q to the frog 37 of switch H, thence through rail 1 of section E—F to the wheels and axles of the train into rail 1^a of section E—F; from this rail the current returns through conductor 36, rail 1 of sub-section P—Q, contact 34 of circuit controller K, rail 1 of sub-section Q—S to the frog 38 of a switch H^A and thence by rail 1^a of section C—D, battery L^P and resistance 6 to the secondary 4 of transformer T^P. It follows that as a train proceeds through the cross-over and along section C—D it is supplied with train controlling current from transformer T^P, but that should relay R^P become de-energized the supply of train controlling current to the rails would be interrupted.

In the modification illustrated in Fig. 4, transformers T^F and T^P are controlled in the same manner as in Figs. 1 and 2, but the exit ends of the rails of sub-section P—Q are connected with the rails of section E—F by means of conductors 41 and 42. Insulated joints 2^a are inserted in the rails 1 and 1^a of section E—F immediately to the right of frog 37 of switch H^P, and a small impedance 40 is connected across each such insulated joint 2^a. The potential drop created in the impedances 40 by train controlling current flowing in the rails of section E—F is effective to cause train controlling current to flow in the rails of sub-section P—Q when a train moves through the cross-over. With the arrangement of apparatus illustrated in this view a train is continuously supplied with train controlling current as it proceeds through the cross-over provided relay R^P is energized.

Referring now to Fig. 5, the cross-over is divided as in Figs. 3 and 4 into sub-sections P—Q and Q—S. The auxiliary transformer T^X has its secondary 8 connected across the rails adjacent the right-hand end of sub-section P—Q. The primary circuit for this transformer may be traced from secondary 11 of transformer G, through wires 18 and 19, front contact 13 of relay R^F, wire 20, contact 15—16 of circuit controller K, wire 39, primary 9 of transformer T^X, and wires 32, 23, and 24 back to secondary 11 of transformer G. Transformer T^P is energized, as in the preceding figures, only when relay R^P is energized, and transformer T^F is energized only when relay R^F is energized and when contact 15—17 of circuit controller K is closed. In explaining the operation of the apparatus I will first assume that the switches of cross-over X occupy their normal positions, and that relays R^F and R^P are energized. Under these conditions transformer T^X is deenergized and transformers T^F and T^P are energized. Train controlling current is therefore supplied to the rails of section C—D by transformer T^P and to the rails

of section E—F by transformer T^F. When the switches of the cross-over are reversed, transformer T^F is de-energized so that no train controlling current is supplied to section E—F by this transformer. The closing of contact 15—16 of circuit controller K completes the circuit for primary 9 of transformer T^X so that train controlling current is supplied to the rails of sub-section P—Q. The current supplied to the rails of this sub-section flows through the frog 37 of the switch H^P and the conductor 36 into rails of section E—F so that a train occupying the portion of the track between point E and point P in the cross-over is supplied with train controlling current from transformer T^X. As this train moves into sub-station P—Q the train is still supplied with train controlling current from transformer T^X. As the train moves through sub-section Q—S and into section C—D to the right of switch H^A the train is supplied with train controlling current by transformer T^P.

It should be pointed out that in each of the several arrangements of trackway apparatus herein shown and described, train controlling current is supplied to the rails of the cross-over under the control of traffic conditions in advance and that the control of the train is therefore continuous in passing from one to the other of the two parallel sections of railway track.

For purposes of explanation I have assumed that the train controlling current is continuous alternating current but this is not essential and the apparatus may be used with any suitable form of train controlling current.

Although I have herein shown and described only a few forms of trackway apparatus embodying my invention, it is understood that various changes and modifications may be made therein within the scope of the appended claims without departing from the spirit and scope of my invention.

Having thus described my invention what I claim is:

1. In combination, two parallel sections of railway track connected by a cross-over having its rails divided to form a forward and a rear sub-section, the rails of said forward sub-section being connected with the rails of one of said sections, means for at times supplying train controlling current to the rails of each said section, and means responsive to the positions of the switches of said cross-over for at times supplying train controlling current to the rails of said rear sub-section.

2. In combination, a right-hand and a left-hand section of railway track, a cross-over connecting said sections and divided to form a forward and a rear sub-section, means for at times supplying train controlling current to each said section, conductors for connecting the rails of each section with the rails of

the adjacent sub-section adjacent the exit end of such sub-section, an insulated joint inserted in one rail of one said section between the point of connection of the associated conductors and the entrance end of such one section.

- 6 3. In combination, a section of railway track provided with a track switch, a sub-section of track connected with the switch, means for at times supplying train controlling current to the rails of said section, and means for connecting the rails of said section with the rails respectively of said sub-section adjacent the exit end of the sub-section in such manner that a train occupying said sub-section is supplied with train controlling current from a point in advance of the train.
- 10 10 4. In combination, a section of railway track provided with a track switch, a sub-section of track connected with the switch, means for at times supplying train controlling current to the rails of said section, an insulated joint in one rail of said section, a resistor connected across said joint, and means for applying along one rail of said sub-section the potential drop created in the resistor by the train controlling current to cause train controlling current to flow in the rail of the sub-section.

- 20 5. In combination, a section of railway track provided with a track switch, a sub-section of track connected with the switch, means for at times supplying train controlling current to the rails of said section, a conductor for connecting the rail of said section which includes the switch frog to the rail of the sub-section which includes the switch frog adjacent the exit end of the sub-section, an insulated joint in such rail of the section between the frog and the point of connection 35 of said conductor, and a resistor connected across said joint.

- 40 6. In combination, a section of railway track provided with a track switch, a sub-section of track connected with the switch, means for at times supplying train controlling current to the rails of said section, two insulated joints one in each rail of the section in advance of the switch, a resistor connected across each said joint, and means for 45 connecting the exit ends of the rails of said sub-section with the rails respectively of said section at points in advance of said joints.

- 55 7. In combination, two parallel railway tracks A and B along which traffic normally moves in the same direction and divided to form sections C—D and E—F respectively, a crossover leading from section E—F of track B to section C—D of track A, and means for supplying train governing current to the 60 rails of said crossover under the control of traffic conditions in advance of section E—F or traffic conditions in advance of section C—D according as the switches of the crossover are in normal or reverse positions.

- 65 8. In combination, two parallel railway

tracks A and B along which traffic normally moves in the same direction and divided to form sections C—D and E—F respectively, a crossover leading from section E—F of track B to section C—D of track A and divided into a forward and a rear section, means controlled by traffic conditions on track A in advance of section C—D for supplying train governing current to the rails of section C—D and of the forward section of said crossover, 70 and means for supplying train governing current to the rails of section E—F and of the rear crossover section under the control of traffic conditions on track B in advance of section E—F or under the control of traffic 75 conditions on track A in advance of section C—D according as the switches of said crossover are in normal or reverse positions.

9. In combination, two parallel railway tracks A and B divided into sections C—D and E—F along which traffic normally moves in the same direction, a cross-over leading from section E—F into section C—D, means controlled by traffic conditions on track A in advance of section C—D for connecting a source of train controlling current across the rails at the exit end of said section, and means for connecting a source of train controlling current across the rails at the exit end of section E—F under the control of traffic conditions on track B or on track A in advance of said sections according as the switches of said cross-over are in normal or reverse positions.

10. In combination, two parallel railway tracks A and B divided into sections C—D and E—F along which traffic normally moves in the same direction, a cross-over leading from section E—F into section C—D, a transformer T^P having its secondary connected across the rails at the exit end of section C—D, a transformer T^F having its secondary connected across the rails at the exit end of section E—F, means controlled by traffic conditions on track A in advance of section C—D for supplying train controlling current to the primary of transformer T^P , and means for supplying train controlling current to the primary of transformer T^F under the control of traffic conditions on track B in advance of section E—F or under the control of traffic conditions on track A in advance of section C—D according as the switches of said crossover are in normal or reverse position.

11. In combination, two parallel railway tracks A and B divided into sections C—D and E—F along which traffic normally moves in the same direction, a cross-over leading from section E—F into section C—D, a transformer T^P having its secondary connected across the rails at the exit end of section C—D, a transformer T^F having its secondary connected across the rails at the exit end of section E—F, a track relay connected with the rails of each track in advance of said sections, a source of train controlling current, 120 125 130

5 a circuit controller operated by one of the switches of said cross-over and having a normal and a reverse position corresponding to the normal and reverse positions of said switch, a circuit for the primary of transformer T^D including said source and controlled by said relay for track A, a circuit for the primary of transformer T^F including said source and said circuit controller in its normal position as well as a front contact of the relay for track B, and a second circuit for the primary of transformer T^F including said source and said circuit controller in its reverse position as well as a front contact of the relay for track A.

10 12. In combination, two parallel railway tracks A and B divided into sections C—D and E—F along which traffic normally moves in the same direction, a cross-over leading from section E—F into section C—D, and means for connecting a source of train controlling current across the rails at the exit end of section E—F under the control of traffic conditions on track B or on track A in advance of said sections according as the switches of said cross-over are in normal or reverse positions.

15 13. In combination, two parallel railway tracks A and B divided into sections C—D and E—F along which traffic normally moves in the same direction, a cross-over leading from section E—F into section C—D, a transformer T^F having its secondary connected across the rails at the exit end of section E—F, and means for supplying train controlling current to the primary of said transformer under the control of traffic conditions on track B in advance of section E—F or under the control of traffic conditions on track A in advance of section C—D according as the switches of said cross-over are in normal or reverse position.

20 14. In combination, two parallel railway tracks A and B divided into sections C—D and E—F along which traffic normally moves in the same direction, a cross-over leading from section E—F into section C—D, a transformer T^F having its secondary connected across the rails at the exit end of section E—F, a track relay connected with the rails of each track in advance of said sections, a source of train controlling current, a circuit controller operated by one of the switches of said cross-over and having a normal and a reverse position corresponding to the normal and reverse positions of said switch, a circuit for the primary of transformer T^F including said source and said circuit controller in its normal position as well as a front contact of the relay for track B, and a second circuit for the primary of transformer T^F including said source and said circuit controller in its reverse position as well as a front contact of the relay for track A.

25 15. In combination, two parallel railway

tracks A and B divided into sections C—D and E—F along which traffic normally moves in the same direction, a cross-over leading from section E—F into section C—D, means controlled by traffic conditions on track A in advance of sections C—D for connecting a source of train controlling current across the rails at the exit end of said section, means for connecting a source of train controlling current across the rails at the exit end of section E—F under the control of traffic conditions on track B or on track A in advance of said sections according as the switches of said cross-over are in normal or reverse positions, and means operating when the switches of said cross-over are reversed for supplying train controlling current to the rails of said cross-over under the control of traffic conditions on track A in advance of section C—D.

30 16. In combination, two parallel railway tracks A and B divided into sections C—D and E—F along which traffic normally moves in the same direction, a cross-over leading from section E—F into section C—D, a transformer T^D having its secondary connected across the rails at the exit end of section C—D, a transformer T^F having its secondary connected across the rails at the exit end of section E—F, means controlled by traffic conditions on track A in advance of section C—D for supplying train controlling current to the primary of transformer T^D , means for supplying train controlling current to the primary of transformer T^F under the control of traffic conditions on track B in advance of section E—F or under the control of traffic conditions on track A in advance of section C—D according as the switches of said cross-over are in normal or reverse position, and means operating when the switches of said cross-over are reversed for supplying train controlling current to the rails of said cross-over under the control of traffic conditions on track A in advance of section C—D.

35 17. In combination, two parallel railway tracks A and B divided into sections C—D and E—F along which traffic normally moves in the same direction, a cross-over leading from section E—F into section C—D, a transformer T^D having its secondary connected across the rails at the exit end of section C—D, a transformer T^F having its secondary connected across the rails at the exit end of section E—F, a track relay connected with the rails of each track in advance of said sections, a source of train controlling current, a circuit controller operated by one of the switches of said cross-over and having a normal and a reverse position corresponding to the normal and reverse positions of said switch, a circuit for the primary of transformer T^D including said source and controlled by said relay for track A, a circuit for the primary of transformer T^F including said source and said circuit controller in its normal position

as well as a front contact of the relay for track B, a second circuit for the primary of transformer T^F including said source and said circuit controller in its reverse position as well as a front contact of the relay for track A, and means operating when the switches of said cross-over are reversed for supplying train controlling current to the rails of said cross-over under the control of traffic conditions on track A in advance of section C—D.

18. In combination, two parallel railway tracks A and B divided into sections C—D and E—F along which traffic normally moves in the same direction, a cross-over leading from section E—F into section C—D, means for connecting a source of train controlling current across the rails at the exit end of section E—F under the control of traffic conditions on track B or on track A in advance of said sections according as the switches of said cross-over are in normal or reverse positions, and means operating when the switches of said cross-over are reversed for supplying train controlling current to the rails of said cross-over under the control of traffic conditions on track A in advance of section C—D.

19. In combination, two parallel railway tracks A and B divided into sections C—D and E—F along which traffic normally moves in the same direction, a cross-over leading from section E—F into section C—D, a transformer T^F having its secondary connected across the rails at the exit end of section E—F, means for supplying train controlling current to the primary of said transformer under the control of traffic conditions on track B in advance of section E—F or under the control of traffic conditions on track A in advance of section C—D according as the switches of said cross-over are in normal or reverse position, and means operating when the switches of said cross-over are reversed for supplying train controlling current to the rails of said cross-over under the control of traffic conditions on track A in advance of section C—D.

20. In combination, two parallel railway tracks A and B divided into sections C—D and E—F along which traffic normally moves in the same direction, a cross-over leading from section E—F into section C—D, a transformer T^F having its secondary connected across the rails at the exit end of section E—F, a track relay connected with the rails of each track in advance of said sections, a source of train controlling current, a circuit controller operated by one of the switches of said cross-over and having a normal and a reverse position corresponding to the normal and reverse positions of said switch, a circuit for the primary of transformer T^F including said source and said circuit controller in its normal position as well as a front contact of the relay for track B, a second circuit

for the primary of transformer T^F including said source and said circuit controller in its reverse position as well as a front contact of the relay for track A, and means operating when the switches of said cross-over are reversed for supplying train controlling current to the rails of said cross-over under the control of traffic conditions on track A in advance of section C—D.

In testimony whereof I affix my signature
HERBERT A. WALLACE.
